UNITED STATES PATENT OFFICE.

JAMES S. ADAMS, OF HASLAM, TEXAS.

SURVEYING INSTRUMENT.

1,174,034.

Specification of Letters Patent.

Patented Mar. 7, 1916.

Application filed April 28, 1915. Serial No. 24,510.

To all whom it may concern:

Be it known that I, JAMES S. ADAMS, a citizen of the United States, residing at Haslam, in the county of Shelby and State 5 of Texas, have invented certain new and useful Improvements in Surveying Instruments, of which the following is a specification.

This invention relates to precision instruments and more particularly relates to an instrument of this character which may be employed by surveyors in calculating the distance between the point of "setting up" and the target, without the use of the usual line 15 ear chain.

As a principal object it is contemplated to provide a surveying transit bearing a pair of pivoted telescopes, one of which is employed to find the elevation of the target by 20 reference to a guide scale while the other telescope coacts with the one first mentioned in automatically registering the distance between the point of "set-up" and the target.

More specifically it is aimed to provide a 25 base plate which may be fitted upon the ordinary tripod, such plate to have pivotally mounted thereon an elevational telescope for moving through vertical angles and a distance telescope for moving through horizontal 30 angles, together with guide scales for each such instrument.

The above and additional objects which will become apparent as this explanatory description proceeds, are accomplished by such 35 means as are illustrated in the accompanying drawings, described in the following specification and then more particularly pointed out in the claims which are appended hereto and form a part of this application.

With reference to the drawings, wherein there is illustrated the preferred embodiment of this invention, as it is reduced to practice and throughout the several views 45 of which like characters of reference designate similar parts: Figure 1 is a plan view of the transit provided by this invention, Fig. 2 is an elevational view of the subject-matter of Fig. 1, Fig. 3 is a sectional detail 50 of the adjusting means for the distance telescope, and Fig. 4 is a side elevational view of the adjusting means for the elevation telescope.

There is employed in the transit of the 55 present invention a base plate 5 which is

substantially rectangular but having one of its ends 6 prolonged to meet the diagonal member 7 in forming an extended corner from which projects the arm 8, parallel to the sides of the plate 5. This arm is formed 60 with a slot 9 in which there is slidably accommodated a block 10, such block being adjustably movable longitudinally of the slot by means of the screw 11, one terminal of which is fitted with the knurled cap 12 65 while the opposite end is cut away at the point denoted 13 to accommodate in the cut away portion a screw 14, which a reference to Fig. 3 will show as permitting rotation of the screw without longitudinal movement 70 thereof.

At some suitable point of the base plate which may be symmetrically determined in accordance with the weight of the telescopes mounted upon said plate, there may be provided the removable pivot screw 15 which rotatably mounts the base plate 5 upon a hub 16 carried upon the upper plate 17 of a tripod designated 18 as an entirety. This tripod has a lower plate 19 vertically spaced 80 from the mentioned upper plate 17 and adjustably maintaining the same through the medium of the customary screws 20 whereby leveling of the base plate 5 is attained in accordance with spirit levels 21 which may 85 be inset into the plate 5 at right angles to each other. Two telescopes are pivotally supported upon this base plate for turning respectively through vertical and horizontal angles. The elevation telescope 22 is pivot- 90 ed to one of the forward corners of the plate through the medium of a yoke 23 and is provided rearwardly with the lateral extension 24 which may be threaded to receive at its extremity the adjusting friction 95 cap 25 which will maintain the telescope in set position with reference to the arcuately slotted guide 26 through which the extension 24 projects. This guide is provided with a scale denoted 27 with which a pointer 100 28 carried by the telescope is adapted to coact in determining degrees of angular elevation of a target. A compass 29 may also be supported by the base plate at some suitable point.

The distance registering telescope 30 is also mounted for passing through vertical angles through the medium of the pivoting yoke 31, itself swivelly mounted upon the base plate 5. Rearwardly this instrument is 110

supported by the ring 32 secured at the upper extremity of an adjusting rod 33, this latter being threaded for vertical movement through the block 10 previously described as 5 slidable in the slotted projection 8. A nut 34 controls vertical adjustment of this rod and a pointer 35 is carried by the block 10 to coact with the scale 36 engraved on one edge of the projection 8. Spirit levels 37 10 are secured as is customary upon each of the telescopes 22 and 30 in order to permit of the device being used as a level when desired.

In operating one of the transits of this 15 invention in order to dispense with tedious use of the surveyor's chain, the tripod is first "set-up" and the base plate leveled up thereupon by adjusting opposite screws 20 in the usual manner. The elevation telescope 22 is 20 then trained upon the target which must be brought to the exact center of vision in the field afforded by the cross hairs of the telescope. The elevation may then be read off upon the scale 27, the latter being suitably 25 laid off in both directions from the zero point which the pointer 28 normally indicates when the telescope is level, those readings on the portion of the scale designated A being plus elevations while the upper portion 30 B of the scale is read for the minus elevations, or depressions from the horizontal line of sight through this telescope. When the elevation has been thus determined both the telescope 22 and the base plate 5 are 35 clamped in their positions while the target is then located through the distance telescope 30 so that the line of sight now taken intersects the line of sight of the elevation telescope at the target itself. A reading is 40 then taken upon the scale 36, the graduations of which are especially calibrated for each transit. It will thus be seen that means have been provided whereby the objects previously presented may be readily attained 45 by this novel embodiment of transit. Aside from surveying the distance across impassable bodies such as quicksand, wide rivers and the like and in otherwise dispensing with the use of the usual chain, this invention 50 provides a precision instrument which may be most readily adapted for use as a range-finder.

While in the foregoing however, there has 55 thus been illustrated in the drawings and described in the specification such combination and arrangement of elements as constitute the preferred embodiment of this invention, it is desired to emphasize the fact that such minor changes in the matters of proportion and degree may be made in later 60 adaptations of this device as shall not alter

the spirit of the invention as defined in the appended claims.

What is claimed is:

1. A surveying instrument including a rotatable base plate, means for leveling and holding said plate against rotation, yokes mounted on opposite sides of said plate, a telescope pivotally supported in each yoke for movement through vertical angles, an arcuate scale frictionally supporting the rear of one of said telescopes, a pointer carried by the latter to coact with said scale, a vertically adjustable rod supporting the other of said telescopes, and means for turning said rod through horizontal angles. 75

2. A surveying instrument including a rotatable base plate, means for leveling said plate and holding the same against rotation, yokes carried by said plate and one thereof 80 swivelly connected thereto, a telescope pivoted in each yoke for movement through vertical angles, an arcuate guide secured to said plate and interiorly slotted, a projection carried by one of said telescopes for extension through said guide, a friction cap for said extension in maintaining said telescope adjustably to said guide, a pointer carried by said telescope, said guide having a scale marked thereon, and means for adjustably 85 supporting the free extremity of the other of said telescopes for movement through both vertical and horizontal angles.

3. A surveying instrument including a rotatable base plate, means as customary for 95 leveling said plate and holding the same against rotation, a pivoting yoke carried by said plate, a swiveled pivoting yoke also carried thereby, an arcuately slotted guide secured to said plate, a telescope mounted in 100 first said yoke for movement through vertical angles, an extension upon said telescope for projection through said guide, said guide having a scale marked thereon, a pointer carried by said telescope, means for 105 frictionally clamping said telescope to said guide, a slotted extension formed on one corner of said plate, a block slidable horizontally in said extension, a telescope mounted in said second yoke for horizontal movement, an adjustable rod passing through said block and also supporting second said telescope, said slotted extension having a scale marked thereon, and a pointer carried by said block to coact with said scale. 110

In testimony whereof I affix my signature in presence of two witnesses.

JAMES S. ADAMS.
